UNITED STATES PATENT OFFICE.

MARIE JOSEPH GEORGES ADOLPHE LEMAISTRE, OF PARIS, FRANCE.

HOT-WATER-HEATING INSTALLATION.

Application filed September 13, 1922, Serial No. 587,878, and in France September 26, 1921.

This invention relates to a hot water heating installation and has for its object to provide an active and regular circulation of the water, whatever the position of the radiators with regard to that of the boiler may be, and even in the case said radiators are placed on a level below the boiler.

One characteristic of the invention resides in that it comprises a pulso-aspirator (designated later on as a pulsator) comprising an upper chamber which is in communication with the hot water pipe and is provided with a depending annular partition, an intermediate chamber having a cross section smaller than that of the upper chamber, and a lower chamber of a still smaller cross-section, the return water pipe extending to the bottom of the lower chamber and being provided with side openings in both upper and intermediate chambers.

The bottom part of the upper chamber is put in communication with the top part of the boiler through adequate piping, and the intermediate chamber is put in communication with the bottom part of the boiler through adequate piping.

Other characteristics of the invention will result from the following description.

In the appended drawings, given by way of example:

Fig. 1 shows diagrammatically a main view of a hot water heating installation, according to the invention.

Fig. 2 shows a detail view of the pulsator.

Fig. 3 illustrates another embodiment of the invention, wherein the pipes connecting the chambers of the pulsator with the boiler are located within the latter.

Fig. 4 shows another embodiment of the invention, wherein the pulsator is disposed outside of the boiler and on the side thereof.

The invention applies to a hot water heating installation of a known type, an embodiment of which is illustrated in Fig. 1, said installation being more fully described in the following:

As shown in Fig. 1, the installation comprises a generator A above which the pulsator D is placed. The latter communicates at its upper end with vertical tubes b contained in a heat exchanger C, by means of a piping d and a valve chamber s. The hot water coming out from the pulsator D after having passed through the tubes b, enters the expansion tank B, through the tube e. Said water can flow out into said ex-

pansion tank through a bell-shaped tubing m¹, the bottom thereof being perforated in order to secure better distribution of the water and to damp the noise. This tank B may be provided with an overflow. When the apparatus begins to function, the water rises normally therein, for instance up to the level X—X'. The hot water is drawn out at the bottom of the tank B, through a pipe e which carries said water to the radiators such as R, R'. After being cooled-down the water comes back through the pipe g¹ to the heat exchanger C in which it surrounds the hot water carrying tubes b. At the upper end of the heat exchanger C, said cool water goes out through the tube g² and passes through a box placed in the tank B, said box enclosing an upper annular container n¹ which is intended to condense the steam contained in the upper part of the tank B and which communicates through vertical tubes with a lower annular container n². The cool water, having been then heated up in the containers n¹ and n², returns to the pulsator through the pipe g, and a check valve s¹ which prevents any backward flowing of the water into the pipe g.

The devices according to the invention which more particularly concern the construction of the pulsator D, together with the means connecting said pulsator with the boiler, are more fully described in the following:

In the embodiment as shown in Fig. 2, the pulsator D comprises an upper chamber 2 containing one or more vertical partitions m which are preferably annular and concentric, said partitions extending from the top wall of the chamber down to the level Z—Z'. In addition to this, said pulsator comprises an intermediate chamber 2^a located below the chamber 2 and having a smaller cross section than the latter. This contraction results in magnifying the fluctuations of the water level below the level Z—Z'. The pulsator comprises also a lower chamber 2^b, of reduced cross section, said chamber being made as long as possible in order to give to the pulsator the height necessary to a satisfactory working of same.

The water return pipe g goes through the three pulsator chambers; it is provided with holes o¹, o² in the upper chamber and with a hole o³ in the intermediate chamber, the lower end of said pipe opening into the lower chamber 2^b at the bottom thereof as

indicated at σ^4 . Holes σ^1 , σ^2 , σ^3 may obviously vary in number.

The upper chamber 2 communicates at its lower end with the upper part of the boiler 5 A through the pipes 3^a and the intermediate chamber 2^a communicates with the lower end of said boiler through the pipes 3^b .

The apparatus works in the following manner:

- 10 The boiler being suitably heated up, steam accumulates mainly in the exterior chamber q which encircles the partition m of the chamber 2 and forces the hot water back into the expansion tank B through the pipe d .
 15 the pipes b and the tube d^1 , said water being at a temperature close to the boiling point. As the steam reaches the lower edge of the partition m it suddenly rises to the upper part of the inside chamber p , thereby
 20 causing condensation of said steam and therefore a resulting drop of pressure. Said drop of pressure creates in the whole water mass of the pulsator, a supervaporization which causes some water and steam to be
 25 driven into the tank B, whereby the upper chamber of the pulsator is entirely emptied. On account of this sudden ejection, the pressure in the pulsator is momentarily reduced, whereby the cool water brought in by the
 30 pipe g is caused to enter said pulsator. This relatively cold water creates condensation effects which accelerate the pressure drop. In that way, the cool water returns to the pulsator with force, first, through the lower
 35 aperture σ^4 , then through the holes σ^3 , σ^2 , σ^1 , while the hot water passes from the tank B into the radiators through the pipe e . Thus, the pulsator is filled up again with water and the working cycle of the apparatus starts over again.

40 Due to the particular construction of the pulsator and of the connecting means of same with the boiler, as described above, the working of the apparatus is very regular and forcible pulsations are obtained without producing any appreciable action upon the mass of water in the boiler 1, so that the latter keeps working at a practically constant rate of vaporization.

45 On account of the very active circulation thus obtained, pipes and radiators of a very small cross-section can be used. Moreover, the pipes are subjected only to the pressure due to the water load; their walls can be
 50 made relatively thin and without mechanical strength, and the joints in proportion. It is obvious that the elimination of air is secured in a better way with the present system than with the thermo-siphon system. The water can return to the boiler at a high temperature (90° C.) without preventing a good working of the apparatus, and the temperature of the water at the beginning of its travel through the system may be very close
 55 to 100° C. The installation can work with

a relatively reduced volume of water, the starting of the system being therefore very rapid. Finally, the position of the boiler is independent of that of the radiators and the latter can be disposed either above or below the boiler.

The radiators can be placed above the expansion tank.

Fig. 3 shows that the tubes 3^a may be replaced by holes provided with short flanges 75 3 and that the outer tubes 3^b may be replaced by tubes such as 3^c , inside of the boiler. An advantageous arrangement consists in utilizing the tubes 3^a shown in Fig. 2, simultaneously with the inner tubes 3^c shown 80 in Fig. 3.

As shown in Fig. 4, the pulsator is disposed outside of the boiler and on the side thereof. It may, in fact, be placed at any distance from the boiler. Its lower end is 85 encircled by a casing E. An annular expansion chamber 4 which encircles the intermediate chamber 2^a , communicates with the lower part of the upper chamber 2 through the pipes 3 and with the upper part of the boiler through the pipe 9. Through the tubes 3^b , the intermediate chamber 2^a communicates with the lower part of the chamber 5 of the casing E, which in turn communicates with the lower part of the boiler 90 through the pipe 10. The use of either a hot water or a steam generator is thus rendered possible, which results in increasing the output of the installation and permitting the use of existing apparatus, a single generator being capable of operating several pulsators. Small holes such as 11 may be provided, so that the upper part of the chamber 5 may communicate with the chamber 2.

Having now described my invention, what I claim as new and desire to secure by Letters Patent is:

1. In a hot water heating installation, the combination with a boiler of a hot water pipe, a cold water pipe, a number of radiating elements, each of which is connected at one end with said hot water pipe and at the other end with said cold water pipe, a pulsating apparatus comprising an upper chamber, an inner depending partition forming in said upper chamber an inner compartment and an outer compartment, connecting means between the inner compartment and said hot water pipe, an intermediate chamber having a smaller cross-section than the upper chamber and in communication with said upper chamber and a lower chamber having a smaller cross-section than the intermediate chamber and in communication 115 with said intermediate chamber, said cold water pipe extending down through the said inner compartment of the upper chamber and through the intermediate and the lower chambers and being in communication 120

through openings with the said inner compartment, with said intermediate chamber and with said lower chamber, means for connecting the lower part of said upper chamber with the upper part of said boiler and means for connecting the said intermediate chamber with the lower part of said boiler.

2. In a hot water heating installation, the combination with a boiler of a hot water pipe, a cold water pipe, a number of radiating elements, each of which is connected at one end with said hot water pipe and at the other end with said cold water pipe, a pulsating apparatus comprising an upper chamber, an inner depending partition forming in said upper chamber an inner compartment and an outer compartment, connecting means between the inner compartment and said hot water pipe, an intermediate chamber having a smaller cross-section than the upper chamber and in communication with said upper chamber and a lower chamber having a smaller cross-section than the intermediate chamber and in communication with said intermediate chamber, said cold water pipe extending down through the said inner compartment of the upper chamber and through the intermediate and the lower chambers and being in communication through openings with the said inner compartment, with said intermediate chamber and with said lower chamber, conduits connecting the lower part of said upper chamber with the upper part of said boiler and tubes connecting said intermediate chamber with the lower part of said boiler.

3. In a hot water heating installation, the combination with a boiler of a hot water pipe, a cold water pipe, a number of radiating elements, each of which is connected at one end with said hot water pipe and at the other end with said cold water pipe, a pulsating apparatus comprising an upper chamber, an inner depending partition forming in said upper chamber an inner compartment and an outer compartment, connecting means between the inner compartment and said hot water pipe, an intermediate chamber having a smaller cross-section than the upper chamber and in communication with said upper chamber and a lower chamber having a smaller cross-section than the intermediate chamber and in communication with said intermediate chamber, said cold water pipe extending down through the said inner compartment of the upper chamber and through the intermediate and the lower chambers and being in communication through openings with the said inner compartment, with said intermediate chamber and with said lower chamber, an expansion chamber at the lower part of said upper chamber, connected therewith and surrounding said intermediate chamber, a casing enclosing the lower portion of said pulsator, pipes connected to said intermediate chamber and opening into said casing, means for connecting said expansion chamber with the upper part of said boiler and means for connecting the said casing with the lower part of said boiler.

In testimony whereof I have signed my name to this specification.

MARIE JOSEPH GEORGES ADOLphe LEMAISTRE.
